ABSTRACT: A hair roller having at least one strip of material containing radially extending resilient hair gripping bristles mounted on the peripheral surface of the curler body and securely held in position without requiring stitching, such as by passing the ends of the strips through slots interiorly into the curler body, or positioning the strip in a slot with overlying edges along opposite strip edges and having a thickness substantially the same as the strip.

HAIR CURLER

This application is a continuation-in-part of my copending application Ser. No. 728,663, filed May 13, 1968, now U.S. Pat. No. 3,438,382. This invention relates to improvements in hair dressing devices, and more particularly, to an improved hair curler designed and constructed to securely hold a rolled tress of hair in position on the head of the user.

Hair curling as practiced today in the home and professional beauty shops involves division of the hair of the user into various tresses or swatches. Each of these tresses is evenly wound on a hair curler and by dampening the curled tress with water or chemicals, or by application of heat or the like, the tress is caused to take the form imparted to the hair by the curler.

As is well known in the art, during the hair waving treatment the hair filaments elongate when dampened with water or waving lotions, and contract during drying. If a curler does not embody adequate means for compensating for the elongations and contractions of the hair filament during the curling process, the hair tress wound thereon frequently becomes loosened and the individual hair filaments become displaced and take the curl form existing under the loosened or displaced condition, which does not produce the optimum curl.

Also, a satisfactory curler should not provide stress concentrations with respect to the hair filaments. Often, after hair-waving lotion has been applied to the tress of hair, the individual filaments become brittle and are usually broken or harmed by any application of a stress concentration. Curlers in widespread use today generally require separate retaining devices to hold a curler in position on the head of the user, such as a clip or bobby pin, or a band or arm, which interconnect the ends of the cylindrical roller and extend over and engage the hair rolled thereon. The bobby pin is the most common hair retainer used, but is difficult to use by the self user, and also applies stress concentrations to the filaments of the hair.

Attempts to overcome these objections have been many and varied. Curlers having circumferential strips of material containing hair gripping strands or bristles have been used, which effectively hold and retain the tress of hair on the curler, but these are expensive to fabricate and to manufacture, hence the cost is relatively high. Also, attaching the strips tightly about the peripheral surface of a relatively rigid roller body has been difficult to achieve consistently. Sewing often fails to make a tight, durable seam and create an uneven surface with an overlapped seam. Adhesives often fail during use with waving solutions.

The present invention contemplates a novel hair curler particularly designed and constructed to provide a twofold purpose. The curler is provided with a relatively rigid, but yielding hair winding cord, whereby an efficient curling operation of the hair may be accomplished, while permitting ready drying of the wet tress of hair. At the same time when the tress of hair is wound on the curler, it is easily retained on the head of the user by merely pushing it against the scalp, whereby yielding bristles on opposite ends of the curler grasp the hair on the scalp and hold the rolled tress of hair securely in position. The curler body has slits which securely retain cylindrical strips of material containing the yielding bristles on the curler body tightly in position on the body, such as ends of the strips on the ends of the roller.

Accordingly, it is an object of the present invention to provide a hair curler on which the hair may be easily rolled on the head of the user and which can be securely retained in rolled position without employing separate external fastening devices.

Another object of the present invention is to provide an improved hair curler designed and constructed for facilitating the dressing of one's own hair and having sufficient rigidity to ensure efficient curling of the hair.

A still further object of the present invention is to provide a hair curler body which can easily and quickly mount strips of material containing hair-holding bristles without stitching, and

yet has an open mesh construction to allow free passage of air to the interior of the curl.

Still another object is to provide a hair curler that accomplishes all of the above and yet is simple to use, inexpensive to fabricate, light in weight, allows free evaporation of any moisture in the hair, and is durable in use.

Further objects and features of the invention will be apparent when the following description is considered in connection with the annexed drawings, in which:

10 FIG. 1 is a front elevational view of a hair curler embodying the present invention;

FIG. 2 is an enlarged cross-sectional view taken along line 2-2 of FIG. 1;

15 FIG. 3 is an enlarged fragmentary cross-sectional view taken along line 3-3 of FIG. 1;

FIG. 4 is an enlarged cross-sectional view similar to FIG. 3 and showing a further modification;

20 FIG. 5 is an enlarged, fragmentary plan view of one end portion of the curler showing a further embodiment of the present invention;

FIG. 6 is a front elevational view of a further embodiment of the present invention;

25 FIG. 7 is a front elevational view of a still further embodiment; and

FIG. 8 is an enlarged cross-sectional view along lines 8-8 of FIG. 7.

Referring now to FIGS. 1-5, a hair curler 10 has a core member 12, which is of generally thin, tubular construction, 30 made of plastic or the like. Advantageously, the central portion 13 of core member 12, about which a tress of hair is wound, has an open mesh design to aid in drying of the tress of hair, which is shown as rectangular grid work. Any convenient type of mesh construction can be used. Core member 12 has

35 at opposite ends cylindrical end portions 14 and 16, respectively. End portion 14 is set off by a pair of annular ribs 18 and 20 and end portion 16 is similarly set off by a pair of ribs 22 and 24. End portions 14 and 16 could have their peripheral surface solid or of mesh construction. Extending between ribs

40 18 and 20 and transverse thereto, is a slot or opening 26. Slot 26 is of a predetermined thickness, which will be discussed hereafter. Disposed circumferentially about end portion 14 is a fabric or strip of material 28, provided with yieldable hair-retaining elements, such as bristles or hooks 30, extending 45 outwardly therefrom. While hooks and bowed pairs of cooperating bristles 30 are shown, other hair-retaining or hair-gripping means may be used, such as crossed bristles. Strip 28 is of sufficient length, so that the entire circumference of end portion 14 is covered and the ends of strip 28 are forced

50 downwardly through slot 26 into the interior of core member 12, such as shown in FIG. 3. Slot 26 has a width sufficient to frictionally receive the ends of the strip 28, so that the double thickness of material in slot 26 is securely held, and so retains strip 28 tightly about the circumference of end portion 14 during use. Also, the hair engaging elements 30 on opposite ends of the strip engage each other in slot 26 and cooperate to

55 securely hold the ends of strip 28 in position within slot 26, such as indicated in FIG. 3 at 32.

60 A similar construction is shown for securely retaining strip 28 on end portion 16.

Advantageously, end portions 14 and 16 have a greater outer diameter than the central portion 13 of curler 10. The enlarged ends facilitate the handling of curler 10 during the winding of the hair thereon, as well as being used to positively engage the hair of the user when the curler is in its rolled position, so as to hold the curler in operative position on the head of the user without requiring the use of external fastening devices, such as clips or pins. To aid in initially holding the ends of a tress of hair to be curled, central portion 13 of curler 10 has radially projecting hair gripping teeth 34, which also prevent lateral slipping of hair along the inner core.

65 In use, a quantity of individual strands of hair in a swatch is spread upon central portion 13 of curler 10 and curler 10 is 70 rotated to wind the tress of hair. The user grips the end por-

tions 14 and 16, and the strips of fabric at 28 mounted on these end portions aid in positively gripping the curler even if the hands of the user are wet and regardless of the lubricating qualities of the hair lotion used. The tress of hair is wound onto the roller device, preferably until the roller 10 is wound up tightly against the scalp of the user and then it is pressed against the head of the user, so that hair gripping elements 30 on strips of fabric 28 grasp and engage the portions of the hair of the user on the scalp, thereby retaining the curler 10 in its operative position without the use of any external fastening device.

To provide a more positive locking of material 28 on curler body 12, as shown in FIG. 4, at least one end 36 of fabric 28 is doubled over when forced through opening 26. This prevents any accidental displacement of the ends of the strips.

A further embodiment is shown in FIG. 5, wherein openings 26 in roller body 12 have serrated edges 38, or a series of pointed teeth, which positively hold material 28 in locked position about the periphery of end portions of 14 and 16. The serrated edges 38 positively hold material 28 in position.

A still further embodiment is shown in FIG. 6, wherein a strip of fabric 40 having bristles 41, is positioned centrally on a roller body 42. Roller body 42 has a longitudinally extending slot or opening 44, which receives the ends of strip 40. The edges of slot 44 could be smooth or serrated as discussed above. Preferably, roller body 42 has ribs 45 to aid in positioning strip 40. Further, strip 40 could be smaller than shown or extend to one or both ends of roller 42.

Another embodiment is shown in FIG. 7 and 8, wherein a roller body 46 has a longitudinally extending strip 48 disposed on opposite sides of its circumference. As seen best in FIG. 8, roller 46 has a shallow dovetail slot or channel 50, which has a depth generally the same as the thickness of strip 48, so as to allow bristles 52 to extend radially beyond the surface of roller 46. The inwardly tapered edges 54 of slot 50 hold strip 48 in place. Strip 48 is slid into slot 50 from one end, which communicates with one end of roller 46. While two strips 48 are shown, one or more can be used as desired.

The degree of rigidity of the core or body members exerts continuous tension on the strands forming the curl, and which automatically adjusts to the tension of the curl during its setting and drying process. The strips of gripping material do not adversely affect this rigidity, and yet allow comfort to the user during the curling operation. Since generally only a portion of the roller has the hair gripping material about the roller peripheral surface, air is freely available to the wet tress of hair to speed drying. Also, the roller is light and flexible. While a tubular curler body is desirable for these reasons, a solid body containing the necessary slot can be used.

The strips of material 28 are securely held in position without sticking or using adhesive heretofore used. While ribs

18, 20, 22, 24 and 45 were shown aiding in positioning strips 28, 40 and 48, they could be eliminated. Also, strips 28, 40 and 48 could be molded with the hair-engaging elements integrally attached. Further, only a single end strip 28 can be used.

While preferred embodiments of the invention have been described above, it will be understood that many variations thereof will be readily apparent to those skilled in the art without departing from the spirit thereof.

10 I claim:

1. A hair curler comprising a generally cylindrical core, said core having at least one longitudinally extending slot in its outer peripheral surface with facing edges, a strip of material disposed on the outer peripheral surface of said core and having

15 a plurality of flexible resilient hair retaining elements extending radially therefrom, portions of said strip being positioned within said slot, and said strip securely retained on said core by the coaction of the facing edges of said slot.

2. A hair curler as in claim 1, wherein the ends of said strip are positioned inwardly through the slot thereby securely retaining said strip about the peripheral surface of said core.

3. A hair curler as in claim 1, wherein said core has a central portion and two end portions, at least one of said end portions having said slot, the ends of said strip being positioned inwardly through its corresponding slot securely retaining said strip about the peripheral surface of said core end portion.

25 4. A hair curler in accordance with claim 1, wherein said covering is a fabric and said bristles are filaments.

5. A hair curler in accordance with claim 2, wherein one of the ends of said strip is doubled over in said slot to tightly hold said strip about its end portion.

6. A hair curler in accordance with claim 3, wherein said core end portions have a greater outer diameter than the central portion.

35 7. A hair curler in accordance with claim 3, wherein each of said end portions are defined by a pair of spaced annular radially outwardly extending ribs.

8. A hair curler in accordance with claim 3, wherein at least one edge of the opening in said end portions is serrated to more tightly hold the ends of said covering.

40 9. A hair curler in accordance with claim 2, wherein the edges of said slot has a series of teeth for firmly engaging the covering about said ends.

10. A hair curler as in claim 1, wherein said slot is dovetailed to hold said strip in position and communicates with one end of said core.

11. A hair curler as in claim 1, wherein the edges of said slot beginning at the outer circumference of the roller are outwardly tapered so as to overlie said strip, said slot having a depth generally the same as the thickness of said strip.

UNITED STATES PATENT OFFICE
CERTIFICATE OF CORRECTION

Patent No. 3,566,886 Dated March 2, 1971

Inventor(s) NATHAN L. SOLOMON

It is certified that error appears in the above-identified patent and that said Letters Patent are hereby corrected as shown below:

In the Specification:

Column 2, line 37 - Change "20 and end portion 16"
--20 and end portion section 16--

Column 3, line 29 - Change "The 7 and 8," to
--Figs. 7 and 8,-

Column 4, line 29 - Change "a hair curler" to
--A hair curler--

Signed and sealed this 21st day of September 1971

(SEAL)
